UNITED STATES PATENT OFFICE

KOBY KOHN, OF NEW YORK, N. Y., ASSIGNOR TO CHATHAM SPECIALTY CORPORATION, OF PITTSBURGH, PENNSYLVANIA, A CORPORATION OF NEW YORK

EXPLOSIVE TOY

Application filed April 29, 1931. Serial No. 533,811.

This invention relates to pyrotechnic devices and particularly to explosive toys, such as salutes and torpedoes.

It is a general object of the present invention to provide a novel and improved type of explosive toy.

More particularly it is an object of the invention to provide a casing for an explosive toy formed from a single piece of tenacious bituminous composition which completely envelops and forms a gas-tight casing for the explosive composition.

An important feature of the invention resides in the formation of the explosive container for a toy pyrotechnic by molding a cup of tenacious material and, after filling in the explosive and any other desired components, closing this cup without the use of any additional parts.

Another important feature of the invention resides in the formation of a toy torpedo in which the outer casing is a unitary structure of molded bituminous material having great tenacity and in which a single striker is secured to an inner wall of the casing in a frangible manner so that it is broken off and acts as a detonator for the explosive material when the torpedo is impacted.

A further feature of the invention resides in a torpedo in which a substantially spherical striker member is arranged within a substantially spherical cavity and is weakly secured to the wall of the cavity to separate therefrom when the torpedo is impacted.

Another feature of the invention resides in the method of forming, assembling, and closing the torpedo casing and detonating means.

Other and further features and objects of the invention will be more apparent to those skilled in the art upon consideration of the accompanying drawing and following specification wherein are disclosed several exemplary embodiments of the invention with the understanding, however, that such changes may be made therein as fall within the scope of the appended claims without departing from the spirit of the invention.

In said drawing:

Figure 1 is a central sectional view taken through one form of torpedo constructed according to the present invention prior to closing and sealing the cup;

Figure 2 is a similar view after the cup is closed and the torpedo completed;

Figure 3 is a view similar to Figure 1 of a modified form of the invention;

Figure 4 is a view similar to Figure 3 showing a step in the process of closing the cup;

Figure 5 is a view similar to Figure 2 showing the second form of the invention in its completed state;

Figure 6 is a perspective view of another form of cup or casing prior to closing; and

Figure 7 is a central section through a salute formed according to the present invention.

In the manufacture of such explosive toys as torpedoes, salutes, and the like, it has heretofore been customary to form the casing or gas-tight container, for the explosive and other essential elements of several parts of the same or different materials. For instance, in torpedoes there may be an inner paper casing formed of two or more parts with an outer covering of paper or a plastic composition, such as wood pulp or flour and an adhesive. Salutes may be formed of a paper tube plugged at the ends with plugs of clay plaster of Paris, glue and paper, glue and sawdust, or various other constructions. It has heretofore been proposed by the present inventor to form the casing of frangible bituminous compositions and to enclose this in a gas-tight flexible covering, but in every case more than one piece has been used in the construction.

In accordance with the present invention, a complete gas-tight casing is made from one single piece of bituminous material which, instead of being brittle or frangible as in prior constructions, is tenacious and resists breaking or cracking under the shock of such impacts as are necessary for the explosion of a torpedo or which may result from the throwing of a salute after it is lighted.

By having the outer casing of one single

piece, all seams are eliminated, and there is no chance for leakage or easy separation of parts, resulting in misfires or weak explosions. Furthermore, the ease of manufacture is much greater and the chances of spoiled articles reduced to a minimum.

The invention is shown in connection with the safety form of toy torpedo wherein no loose gravel or other detonating means are used and also in connection with a globular form of salute, but it will be apparent that the invention could be applied with equal facility to any of the various commercial forms of torpedoes and salutes where it is desirable to have a tenacious one-piece casting or envelope for the explosive.

Referring now to the drawing and particularly to Figures 1 and 2 for an example of the invention, it will be seen that the casing is composed of a single piece 10 of bituminous plastic material, such as fully disclosed in my copending application Serial No. 498,503, filed November 26, 1930, for plastic composition. For convenience in manufacture, this is first formed by a simple molding operation to the shape illustrated in Figure 1, in which there is a semi-spherical portion 11 having walls of substantially uniform thickness so as to form the semi-spherical inner cavity 12, and extending from this bottom portion is the substantially cylindrical portion 13, slightly less in external diameter than the diameter of the semi-spherical portion, producing the reduced or converging section 14 at the junction. The walls of the portion 13 are thinner than those of the semi-spherical portion as shown.

The detonating means, striker, or similar device for exploding the composition is preferably in the form of a sphere 15 which may be molded from the same composition as the cup or made from any suitable material. In the form shown, it is provided with a weight 16 to increase its momentum when it functions to detonate the explosive. It will be appreciated that the weight need not be of the spherical form shown but can be of any shape or can be incorporated as fine particles, such as filings, and disseminated throughout the mass of the plastic composition from which the striker is formed.

The striker is placed within the cup and caused to adhere to the wall of the cavity therein in any suitable manner so that it is sufficiently secure to insure against separation in the ordinary processes of manufacture and shipping of the device and yet so that it will break loose when the torpedo is impacted by throwing it against a hard surface.

For causing the striker to adhere to the cup, resort may be had to several expedients. For example, a portion of the surface of the striker may be heated before it is dropped

into the cup so that the plastic material is softened to cause adhesion between the two. Similarly the cup alone can have a portion heated, or portions of both may be heated and brought together. Preferably, however, the ball is merely dropped into the cup and has poured over it a film of a suitable bituminous mastic in a heated state which will run over it and form the enveloping layer or cover 17 which runs down and also engages the cup as at 18.

To secure more complete adhesion to the cup, some means may be resorted to for extending the surface thereof, such as by forming the annular groove 19 therein into which the quick setting adhesive runs. This adhesive material should be of such characteristics that it fractures sharply on sudden impact, and the added weight imparted to the ball assists in providing the momentum for this fracturing. The ball may be arranged substantially tangent to the inner surface of the cup, as shown in Figure 1, or the portion of the cup on which it rests may be elevated in the form of a short pedestal so that if the ball leaves in a direction at right angles to the base on which it rests, there will be an opportunity for an impact rather than a mere rolling contact with the cavity wall.

After the ball is in position, granular abrasive material which has been previously heated is introduced into the cup so that it softens the surface of both the striker and the cup cavity wall and adheres thereto, after which the excess material is poured out, leaving a coating 20 of granular material on the interior of the cup as high as the line 21 and a similar coating 22 on the surface of the ball or striker or the mastic covering thereon. It may be found that the ball can be adequately secured to the cup merely by the adhesion produced by the heat of the abrasive and by the interlocking of the abrasive particles near the junction of the ball and the cup wall.

When the article is completed to the extent illustrated in Figure 1, it is closed by a suitable manipulation of the cylindrical wall 13, preferably by the use of heated rollers as more fully explained in connection with the modification illustrated in Figures 3, 4, and 5, so that, without the addition of any material or parts, the casing is brought to the configuration illustrated in Figure 2 and is substantially spherical on the exterior and has a substantially spherical cavity 23 therein. As shown in Figure 2, the portion 24 is homogeneous and thicker than the wall 11 of the initially formed portion of the cup. This is to produce sufficient strength where the cup has been formed over and not molded under high pressure as was the initial portion of the cup. This insures sub-

stantially uniform strength for the casing wall.

A torpedo constructed according to this arrangement has but two parts, and they are secured together. This insures simplified manufacture and great safety in manufacture and in transit. By having both the cavity and the striker of substantially spherical form and each covered with abrasive, it will be seen that a misfire is almost impossible, for after the ball breaks loose, it will roll around within the cup, striking at a number of places and insuring ignition. It has been found from a large number of experiments that, even though the torpedo strike at the point 25 when thrown, the ball will break away by rebounding and will strike against the opposite wall of the cavity and insure detonation.

In the form shown in Figures 3, 4, and 5, the cup 26 is formed to substantially the same configuration as shown in Figure 1 but is provided with the overhanging annular ledge 27 at the junction of the neck 28 with the parti-spherical portion, and the shoulder thus formed provides a support for the button 29 which carries the striker 30 as an integral part thereof. This button 29 and its striker part are molded from suitable plastic material, such as a frangible bituminous composition, and the striker may be loaded as by the weight 31. The button has a convex top 32 which substantially follows the configuration of the inner wall 33 of the cavity and is reduced as at 34 to fit within the ledge. It has the frusto-conical surface 35 presented to the interior of the cavity and is attached to the ball at 36 by the reduced integral neck which is sufficiently frangible to break under the conditions set forth in connection with the description of Figure 1. If desired the ball and button may be suitably molded of different materials.

Prior to inserting the button and striker, the inner wall of the cavity up to the ledge is coated with abrasive as at 37. Similarly the surface of the ball and, if, desired, the frusto-conical surface 35 are covered with a coating of abrasive 38 so that, when the ball breaks loose on impact, ignition will take place by the contacting of two abrasive surfaces.

For closing this as well as the first form of the invention, resort may be had to one or more rollers 39 of the configuration shown, and either of these rollers or the torpedo casing are mounted to rotate about the axis 40. The rolling is started at the junction 14 or 41 of the spherical and cylindrical portions, and the rollers are advanced in the direction of the arrows as the rolling proceeds, following, of course, a line parallel to the final desired curvature of the surface. These rollers must be suitably

heated to soften the plastic material to cause it to flow, and as they are advanced toward each other, a portion 42 of the material is caused to flow ahead of them and form a closure which seals itself to a homogeneous mass along the line 40, insuring absolute gas-tightness. In order that this portion 42 may be brought down to the configuration of the body of the torpedo and at the same time thicken and reinforce it over the frangible button, a suitable roller is used to form it down as shown at 43 in Figure 5, where the lines 44 represent the junction of this mashed-out portion and the original surface formed by the rollers 39.

In Figure 6 is shown a different form of configuration for the cylindrical wall which may be applied to either of the types of torpedoes heretofore described. In this arrangement one half 47 of the cylindrical wall is lower than the other half 48 and in the final closing operation is preferably first turned in by the use of heated rollers or the like, and thereafter the other portion 48 is folded down and over to insure a large area of contact between the two parts and to effect a more perfect sealing against the infiltration of moisture or the leakage of the expanding gases resulting from the explosion.

In Figure 7 the invention is shown as applied to a salute or firecracker. In this arrangement the initial construction of the cup is identical with that shown in Figure 3. The button 50, however, instead of being provided with a striker, is centrally perforated and has passing therethrough the fuse 51. The button may be either molded about the fuse or merely drilled and the fuse inserted. The button is, of course, placed in position after the explosive material 52 is introduced, and after the button is positioned, the upper portion 53 of the casing is formed down about the fuse in the manner illustrated in Figure 4, an effort being made, however, to prevent the added portion of material forming about the fuse if possible, although there is no objection to this material being formed as a tube about the fuse.

The invention may be considered to reside mainly in the formation of the casing from a single piece of resilient tenacious composition which can be first molded to cup form and later closed by working or manipulating to form a single-piece gas-tight casing which resists breaking to the extent of remaining intact under ordinary shocks but which will break by the expansion of the gases resulting from the explosion and, in so breaking, form sufficiently small pieces as to offer but little danger from flying particles. Furthermore, the material is such that the heat of the explosion causes the edges to become softened and rounded so that even if

a person is struck by them, no injury is done because of the comparatively smooth edges and the softness of the material at the time.

A further essential feature of the invention is the arrangement of the large striker member which is frangibly secured to the tenacious wall of the casing and which has sufficient weight to be broken loose on impact without damaging the wall of the casing. It must not be overlooked that, when applying a weight in the form of a single part to the striker, this weight is preferably arranged eccentric thereto to insure an erratic movement of the striker within the casing to insure detonation.

Having thus described the invention, what is claimed as new and desired to be secured by Letters Patent is:

1. In a toy torpedo, in combination, a one piece totally enclosing casing of tenacious material, explosive therein, a single striker member rigidly supported from the casing by means breakable when the torpedo is impacted, the breaking of the means leaving the casing intact.

2. In a toy torpedo, a one piece, gas-tight casing completely enveloping an explosive compound, and forming the sole effective enclosure therefor said casing being formed of a tenacious material which remains gas-tight after the impact for producing the explosion.

3. In a toy torpedo, in combination, an explosive, a detonating device and a single covering therefor comprising a totally enveloping gas-tight casing of one piece of heat softened moldable material having sufficient tenacity to resist cracking on the impact necessary to detonate the explosive.

4. In a toy torpedo, in combination, a casing of tenacious, water-proof material, a substantially spherical cavity therein, explosive in said cavity and a substantially spherical striker member in said cavity to detonate the explosive by impact when the torpedo is projected against a hard surface.

5. In a casing for an explosive toy, in combination, a single ply, unsupported, one piece envelope of gas-tight construction, said envelope being formed from tenacious material which remains intact until disrupted by the explosion.

6. In a toy torpedo, in combination, a casing comprising a single ply, one piece envelope of gas-tight construction formed from tenacious material which remains intact until disrupted by the explosion, explosive in the cavity of said envelope, a striker frangibly carried directly by said envelope and means to explode the explosive when said striker is broken loose by impacting the torpedo.

7. In a toy torpedo, in combination, a completely enveloping casing of tenacious material having a cavity therein, explosive

directly in said cavity and in contact with the walls thereof, a striker and button formed integrally, said button being molded into a wall of said cavity with the striker projecting into the cavity, said button and striker being formed of frangible material.

8. A one-piece container for explosive for a toy torpedo having walls defining a compartment for explosive, the inner surfaces of said walls being directly coated with abrasive, a substantially spherical striker covered with abrasive and means weakly securing said striker to an inner surface of said walls.

9. The method of making a torpedo comprising, molding an open cup of tenacious material, applying abrasive to the inner wall thereof, inserting explosive, securing a striker weakly to said cup and within the same and forming the walls of the cup to close the same in a gas-tight manner.

10. The method of making a torpedo comprising molding a cup with an open mouth, forming an abrasive surface on the cavity wall thereof, introducing an explosive and a striker in the cavity and forming the walls of the mouth to provide a closure for the cup.

11. In a toy torpedo, in combination, a gas-tight casing having a substantially spherical cavity therein, explosive in said cavity, a substantially spherical striker in said cavity and attached to the wall thereof and a weight in said striker and eccentric thereto.

12. A striker for a toy torpedo formed of molded plastic material substantially spherical in form, and a weight eccentrically embedded in said molded sphere.

13. In a toy torpedo, in combination, a single piece, closed, gas-tight casing having a substantially spherical cavity therein, a substantially spherical separate striker element tangent to the cavity wall, means frangibly securing said element to said wall, abrasive covering the wall and striker, and explosive filling a portion of the residual cavity.

14. The method of forming a toy torpedo comprising forming a cup with substantially spherical inner and outer bottom walls and substantially straight sides, forming a striker ball, inserting the ball in the cup cavity, securing the ball to the cavity wall, applying abrasive to the cavity wall and ball, depositing explosive in the cavity and molding the walls of the cup to close and complete the spherical configuration thereof.

15. The method of forming a toy torpedo comprising molding a cup of tenacious bituminous composition, inserting explosive and detonating means in said cup and forming over the walls of the cup to completely

enclose the explosive and detonating means in a gas-tight casing.

16. A toy torpedo having a totally enclosing casing of one piece of tenacious bituminous material and a striker within said casing and secured to a wall thereof by a brittle bituminous material.

17. A toy torpedo having a gas-tight casing of tenacious, bituminous plastic forming 10 an inner cavity for explosive, a striker member in said cavity and frangible bituminous material securing said striker to a cavity wall.

18. The method of making a toy torpedo 15 comprising molding a plastic composition to form a cup, inserting a plastic striker in said cup, substantially surrounding the striker with a molten plastic material, in sufficient quantity to drain onto the inner 20 wall of the cup to join the striker and cup, applying hot abrasive to the inner walls of the cup and to the plastic material, inserting explosive and closing the cup.

19. A casing for use in manufacturing a 25 toy torpedo, said casing being molded of a tenacious, bituminous material and having a hollow semi-spherical portion and a substantially cylindrical hollow portion extending from the open end thereof and adapted 30 to be molded over to complete the spherical configuration of the casing, the quantity of material in said cylindrical portion being such as to produce a thicker wall in the portion formed therefrom than in the initially 35 semi-spherical portion.

20. The method of making a toy torpedo comprising molding from tenacious bituminous material a cup having an open mouth, inserting explosive and detonating 40 means into the cup, molding the wall surrounding the mouth to close the mouth and uniting the edges of the mouth to form a homogeneous casing for the torpedo.

21. The method of making a disruptive 45 device comprising forming an open mouthed container of material at least partially softened by heat, inserting a material in said container which is rendered disruptive thereof when changed in state, inserting in 50 to the container means for initiating such change of state and closing the mouth by forming it together to unite the edges thereof to form a substantially homogeneous casing.

55 22. The method of making a firework comprising forming an open mouthed casing of moldable, tenacious material, inserting a pyrotechnic compound and igniting means therefor into said casing, forming the 60 edges of the mouth to close the same and uniting the edges to provide a homogeneous, gas tight casing.

In testimony whereof I hereunto affix my signature.
